Attorney

UNITED STATES PATENT OFFICE.

WILLIAM W. BLAKELY, OF DEXTER, MICHIGAN.

DOUBLE-DECKING DEVICE.

Application filed April 20, 1925. Serial No. 24,633.

My invention relates generally to devices for holding merchandise upon suitable supports and refers more particularly to devices that are adapted to be mounted upon the 5 floors of freight cars and the like, for holding vehicles in an elevated position.

One of the objects of my invention is to provide a simple and durable device which may be quickly and easily set up upon any 10 suitable support and is sufficiently braced so that it will stand up under strains and stresses to which it is likely to be subjected when the support upon which it is mounted is in motion.

15 A further object is to provide a device of this type that is simple in construction and can be manufactured at a comparatively low cost.

With the above and other objects in view, 20 the invention consists of certain novel features of construction, combinations and arrangements of parts as will be more fully described and particularly pointed out in the appended claims.

25 In the accompanying drawings:

Figure 1 is a side elevation of a device embodying my invention.

Figure 2 is a perspective view thereof.

30 Figure 3 is a fragmentary perspective view thereof.

Figure 4 is a fragmentary end elevation thereof.

Figure 5 is a perspective view of one of the anchor plates.

35 Figure 6 is a perspective view of another anchor plate.

Figure 7 is a perspective view of one of the clamps.

40 Figure 8 is a perspective view of the assembled anchor plates and clamp and showing one of the uprights in dotted lines.

Figure 9 is a detail perspective view of one of the tie members and cover plates.

45 Figure 10 is a fragmentary perspective view of one of the beams and showing a clamp attached thereto.

Figure 11 is a fragmentary side elevation of one of the beams and showing a portion of the upper structure of my device mounted thereon.

50 Figure 12 is a detail perspective view of an eye of one of the tie members.

Figure 13 is a sectional view taken on the line 13—13 of Figure 12.

55 Figure 14 is a fragmentary side elevation of a slightly modified form of construction.

Referring now to the drawings, in which like characters of reference designate corresponding parts throughout the several views, the numeral 1 designates a device embodying my invention that is adapted to be mounted upon a suitable support, such as the floor 3 of a freight car, flat car, boat, and the like, for holding an article of merchandise, such as an automobile, in elevated position. 60 As shown, this device is preferably formed of two inverted U-shaped sections 4 and 5 respectively, which are preferably spaced apart a sufficient distance and are of sufficient height to permit another article of 70 merchandise, such as an automobile (not shown), to be placed on the floor 3 beneath the automobile 2. These sections 4 and 5 may be constructed of any suitable material, but are preferably formed of wood. The 75 horizontal beams 7 of the sections preferably extend longitudinally of the automobile 2 at each side thereof, and are preferably of sufficient length to project beyond the opposite ends of the automobile, while the upright 80 members 8 of the sections 4 and 5 preferably incline inwardly and cross the beams 7 immediately below the wheel hubs 9 of the automobile. The upright members 8 preferably carry the load and for this purpose are 85 preferably provided at their upper ends with suitable recesses 10 to receive the wheel hubs 9. For connecting the upright members 8 to the beams 7, I preferably provide suitable U-shaped clamps 11 that are sleeved upon the 90 upright members 8, preferably above the beams 7, and are provided at their lower edges with laterally-extending flanges 12 that are secured to the upper faces of the beams 7. Inasmuch as the beams 7 do not 95 carry the load, any suitable means, such as the nails 13, will suffice for securing the flanges 12 to the beams 7.

For holding the automobile 2 in position, I preferably provide suitable inverted U-shaped tie members 14 that extend over the wheel hubs 9 and are held against the inner sides 15 of the clamps 11 by means of suitable plates 16. As shown, these plates 16 are provided with embossed portions 17 for 105 receiving the arms 18 of the tie members 14 and are held in place by suitable nails 19 that extend through suitable openings 20 in the inner sides 15 of the clamps 11 and engage the upright members 8. To prevent 110 accidental disengagement of the parts, the arms 14 of the tie members are preferably

provided at their lower ends with outward extensions 21 that preferably project through suitable openings 22 in the embossed portions 17 of the plates 16.

5 Although any suitable means may be employed for securing the upright members 8 to the floor 3 of the freight car, I preferably provide suitable anchor plates 23 and 24 respectively and the U-shaped clamps 25. 10 As shown, the plates 24 are adapted to rest upon the floor 3 and are provided with up- 15 standing tongues 26 for engagement with the outer sides of the upright members 8, while the plates 23 are adapted to rest upon the plates 24 and are provided with up- 20 standing tongues 27 for engagement with the inner sides of the upright members 8. To facilitate attachment, the plates 23 and 25 respectively are provided with suitable 25 openings 28 and 29 respectively that are adapted to register when the tongues 26 and 30 27 engage the upright members 8 so that suitable headed elements, such as the nails 30 may be driven through the plates and 35 into the floor 3 for securing the parts in assembled position. When the plates 23 and 40 24 are assembled the clamps 25 are then slipped upon the upright members 8 so that 45 they embrace the upstanding tongues 26 and 30 27. When these parts are assembled suitable headed elements, such as nails 31, are 45 preferably driven through registering open- 50 ings in the clamps 25 and tongues 26 and 27 respectively, for rigidly securing these parts 55 to the upright members 8. Thus the clamps 25 and tongues 26 and 27 materially reinforce the upright members and will effectively prevent the same from splitting when 60 they are formed of wood.

40 For reinforcing the sections 4 and 5 respectively I preferably provide brace rods 32 that cross each other beneath the beams 32 7 and are terminally secured to the clamps 11 and 25 respectively on the upright mem- 45 bers 8. As shown, these brace rods 32 are preferably provided at their opposite ends with suitable reinforced eyes 33 that extend 50 beyond the apertured ears 34 and 35 respec- 55 tively of the clamps and receive the clamp- 60 ing bolts 36 and 37 respectively, extending 65 through suitable apertures in the ears 34 and 35.

55 For holding the beams 7 in properly spaced relation, I preferably provide suitable brace rods 38 that cross each other at the opposite ends of the automobile 2 and are terminally secured to the floor 3 and to the extended portions 39 of the beams 7. As 60 shown, these rods 38 are also preferably provided at their opposite ends with reinforced eyes 40, however, the eyes at the upper ends of the rods 38 preferably extend between the spaced ears 41 of the suitable U-shaped clamps 42 sleeved upon the extended 65 portions 39 of the beam 7 and receive the

clamping bolts 43, while the eyes at the lower ends of the brace rods 38 are preferably secured to the spaced upstanding lugs 44 of suitable anchor plates 45 that are rigidly secured to the floor.

70 Thus, from the foregoing description, it will be readily apparent that I have provided a very simple and durable device that may be very quickly and easily set up or taken down as desired. Moreover, the arrangement is such that the automobile 2 may be mounted upon the uprights 8 of the device without interfering with the automobile or other article of merchandise that is placed on the floor 3 beneath the beams 7. Inasmuch as the beams 7 project beyond the opposite ends of the automobile 2, it is also apparent that the cross rods 38 may be readily applied or removed as desired without interfering with any of the other parts. If 80 desired, suitable headed elements such as the nails 46 may be used to secure the clamps 42 to the extended portions 39 of the beam 7 to prevent the clamps 42 from slipping on the beams. In order that the device may be 85 readily taken apart, I preferably use double-headed nails so that they may be readily withdrawn from the wooden beams and uprights. Thus, these parts, as well as the metal parts may be packed compactly for 90 shipment whenever desired.

95 In Figure 14, I have shown a slight modification in which the U-shaped tie members 50 used to hold the wheel hubs 51 of the automobile in the recessed portions 52 of the 100 upright members are preferably held against the inner sides 53 of the clamps 54 by suitable headed elements, such as the nails 55 which are driven through the inner sides of the clamps and into the upright members. 105 With this construction, the cover plates 16 are dispensed with entirely and the arms 56 of the tie members 50 are preferably provided at their lower ends with laterally offset portions 57 that have suitable openings 110 58 for receiving the nails 55.

115 While it is believed that from the foregoing description the nature and advantages of the invention will be readily apparent, I desire to have it understood that I do not limit myself to what is herein shown and described, and that such changes may be resorted to when desired as fall within the scope of what is claimed.

120 What I claim as my invention is:

1. The combination with a vehicle and a support therefor, of means on the support for holding the vehicle in elevated position including upright members supporting the wheel hubs of the vehicle, clamps secured to said upright members at the upper ends thereof, anchor plates secured to said support adjacent to the lower ends of said upright members, and bracing means connect- 125 ing the clamps at the upper ends of the 130

members to the anchor plates at the lower ends of the members.

2. The combination with a vehicle and a support therefor, of means on the support for holding the vehicle in an elevated position including spaced sections having upright members extending between the wheel hubs of the vehicle and the support, and beams secured to the upright members of each section, said beams projecting beyond the opposite ends of the vehicle, clamps secured to said beams at the opposite ends thereof, and tension means connecting said clamps to said support.

15 3. The combination with a vehicle and a support therefor, of means on the support for holding the vehicle in an elevated position including spaced upright members extending between the wheel hubs of the vehicle and the support, beams extending transversely of said upright members, and means for connecting the beams to the upright members including clamps embracing the members having flanges secured to the beams.

25 4. The combination with a vehicle and a suitable support, of means on the support for holding the vehicle including posts extending upwardly to the hubs of the vehicle, and means for holding said posts in upright position including beams secured to pairs of said posts, and tension members connecting said beams to said support.

35 5. The combination with a vehicle and a suitable support, of means on the support for holding the vehicle in an elevated position including two laterally spaced substantially U-shaped sections arranged in inverted position with the base of each U uppermost, means for bracing said sections including intersecting members terminally secured to said support and the upright members of said sections, and tension means at the opposite ends of said sections urging the latter inwardly toward each other in-

cluding intersecting members terminally secured to said support and the bases of said sections.

6. In a device of the class described, the combination with an upright member for supporting a vehicle, of means for connecting said member to a suitable support including plates having upstanding flanges engaging opposite sides of said member, a common means for securing said plates to said support, and a common means securing said flanges to said upright member.

7. In a device of the class described, the combination with an upright member for supporting the vehicle, of means for connecting said member to a suitable support including a plate secured to the support having an upstanding tongue engaging the upright member, and a clamp holding the tongue in engagement with the upright member.

8. In a device of the class described, the combination with an upright member for supporting a vehicle, of means for connecting said member to a suitable support including plates arranged in superposed relation upon said support having flanges projecting upwardly upon opposite sides of said member, and a clamp embracing said flanges and upright member.

9. The combination with a vehicle and a support therefor, of means on the support for holding the vehicle in an elevated position including spaced upright members extending between the wheel hubs of the vehicle and the support, and means for securing the upright members to the support including anchor plates secured to the support having tongues secured to the upright members, and clamps embracing said upright members and tongues.

In testimony whereof I affix my signature.

WILLIAM W. BLAKELY.
